UNITED STATES PATENT OFFICE.

FREDERIC W. HAWKES, OF NEW YORK, N. Y.

HOLDER FOR NEEDLES AND THE LIKE.

No. 922,893.

Specification of Letters Patent. Patented May 25, 1909.

Application filed June 12, 1908. Serial No. 438,219.

To all whom it may concern:

Be it known that I, FREDERIC W. HAWKES, of New York, in the county of New York and State of New York, have invented certain new and useful Improvements in Holders for Needles and the Like; and I do hereby declare the following to be a full, clear, and exact description of the invention, such as will enable others skilled in the art to which it appertains to make and use the same.

This invention relates to improvements in holders for needles and the like,—one object of the invention being to provide convenient and sufficient means for the retention and safe keeping of needles and the like, and which shall be simple and economical in construction.

A further object is to so construct a needle case and cushion that the same can be readily fitted into the axial opening of an ordinary spool of thread, and to so construct the device that it shall be retained within the spool in a manner to prevent its accidental displacement from any cause.

A further object is to so construct a device of the character above mentioned that it will also serve to retain the loose end or ends of thread.

With these objects in view the invention consists in certain novel features of construction and combinations of parts as hereinafter set forth and pointed out in the claims.

In the accompanying drawings, Figure 1 is a sectional view showing one embodiment of my invention. Fig. 2 is a sectional view showing the application of the device to a spool. Fig. 3 is a plan view of the structure shown in Figs. 1 and 2. Fig. 4 is a perspective view of the needle cushion. Figs. 5, 6, 7, 8, 9, 10 and 11 are views illustrating various modifications.

1 represents a socket piece which may be made of sheet metal or other suitable material and its lower end is closed, as shown at 2. This socket piece is adapted to enter the axial bore of a spool, and, on account of the various sizes of the bores of spools the socket piece will be constructed in a manner to permit its expansion or contraction and thus enable it to be inserted into the bore of a spool regardless of the diameter of the bore and to closely hug the wall of said bore so as to have sufficient frictional contact therewith to prevent the accidental displacement of the socket piece. The socket piece 1 may be thus caused to fit tightly within the spool in

various ways: For instance, it may be provided with longitudinal corrugations, as shown at 3 in Fig. 1, or a ring or collar 4 of rubber or other material which would offer 60 friction, may be placed on the socket piece and, by its frictional contact with the wall of the bore in the spool, prevent accidental displacement of the socket piece, such collar being shown in Fig. 5. The socket piece 1 65 may also be made adaptable to the bore of the spool by slitting it as shown at 5 Fig. 7, or by slitting the socket piece spirally as shown at 6 Fig. 9, or said socket piece may be slotted as shown at 7 Fig. 11. 70

Instead of retaining the socket piece in the bore of the spool by causing frictional contact thereof with the wall of said bore, said socket piece may be threaded as seen at 8 Fig. 10, which threads will impinge against 75 the wall of the bore. The threads 8 also serve another purpose which will be herein-after explained.

The socket piece 1 is open at its upper end and provided with an annular flange 9 which 80 is adapted to act as a stop for the socket piece to prevent the latter from passing completely through the spool. The flange 9 may be made integral with the tubular socket piece or it may be made in the form of an annular 85 disk and secured to the upper open end of said socket piece, but in either case it will be provided at its periphery with a lip 10 adapted to engage the end of the spool. The flange or disk 9 not only serves as a stop to 90 prevent the socket piece from being pushed too far through the spool, but it also serves to receive advertising matter which may be stamped therein or applied by means of a suitable label. The lip 10 will also serve as a 95 retaining device for the loose end of a thread. Instead of making the flange or disk 9 circular, it may be made angular, as illustrated in Fig. 6, and may be provided with a notch 11 forming a thread cutter. When the flange or 100 disk 9 is made angular its corner will be preferably somewhat rounded and it will prevent the rolling of a spool when placed upon a flat surface.

In the construction shown in Fig. 1 the 105 socket piece is closed at its inner end but the socket piece may be formed as a straight tube open at both ends and its lower end then closed by means of a stopper 12 of cork or other suitable material. Instead of providing the socket piece with a flange or disk, such as 9, it may be provided with an annu-

lar bead 13 (Fig. 7) and the tube may be extended above said bead so as to project beyond the end of the spool to be grasped for inserting said socket piece into a spool or withdrawing it therefrom.

The socket piece above described receives a removable holder 14 for a needle cushion 15. The holder 14 is made tubular in form and may be slit or slotted so as to cause it to closely embrace the cushion 15 which is placed therein. Such slotting or slitting of the holder will also enable it to be adapted to the inner wall of the socket piece and made to engage the same with sufficient frictional contact to prevent its displacement. At one end the holder 14 is provided with an inwardly projecting annular lip 16 which will prevent the cushion 15 being forced beyond its upper end, the lower end of said cushion preferably being permitted to project beyond the lower open end of the tubular cushion holder 14. Between its ends the cushion holder 14 is provided with an annular bead 17 to engage the upper open end of the socket piece 1 and thus prevent the cushion and its holder from being inserted too far into the socket piece 1, while that portion of the holder 14 above the bead 17 serves as a handle to be grasped by the user for withdrawing the holder and its cushion from the socket piece when the use of a needle is desired.

If desired the socket piece might be omitted and the cushion holder placed directly in the bore of the spool and made to have frictional contact with the wall thereof. In some cases it might be desired to omit the holder 14 and place the cushion 15 in a removable socket piece having an open lower end.

40 The cushion 15 may be made of any suitable material, rolled into cylindrical form, as seen in Fig. 4, and if desired the needles may be placed in position and rolled with the material composing the cushion. In this way the needles may be properly separated from each other and made readily accessible. It will of course be understood that the cushion will receive needles temporarily as illustrated in Fig. 2.

50 The cushion holder may be provided with an enlarged end portion 18 which may rest on the end of the spool and receive a cushion 19 for the accommodation of needles or pins which may be placed temporarily therein.

55 The cushion holder may be held by frictional contact within the socket piece as before explained or it may be provided with threads 20 to mesh with the threads 8 as shown in Fig. 10.

60 Various other slight changes in details of construction might be made without departing from the spirit of my invention or limiting

its scope and hence I do not wish to restrict myself to the particular forms described nor to the use of my invention for needles, as pins 65 may also be stored in the manner described.

Having fully described my invention what I claim as new and desire to secure by Letters-Patent, is,—

1. A spool attachment which comprises a 70 needle cushion and a holder therefor, each of substantially the diameter of the spool bore, the holder consisting of a hollow cylinder open at both ends and having a longitudinal slit to permit contraction and expansion, said 75 cylinder having also a radial annular flange projecting intermediate its length.

2. In a device of the character described, the combination with a socket piece adapted to be fitted in the bore of a spool, of a cylindrical cushion, and a holder to enter said socket piece and removably hold said cushion therein.

3. In a device of the character described, the combination with a socket piece adapted 85 to engage the wall of the bore of a spool and prevent accidental displacement of said socket piece from said spool, of a cylindrical cushion and a holder for the cushion to enter the socket piece and removably hold the 90 cushion in the latter and prevent its accidental displacement therefrom.

4. In a device of the character described, the combination with a socket piece adapted to be held in the bore of a spool and provided 95 at one end with a flange or disk to be disposed over the end of a spool, of a cylindrical cushion, and a holder for said cushion removably held in said socket piece.

5. In a device of the character described, 100 the combination with a socket piece adapted to be held in the bore of a spool and provided at one end with a flange or disk to overhang one end of the spool, said flange or disk having a peripheral lip projecting toward the 105 bead of the spool, of a holder adapted to be held removably in said socket piece, and a cylindrical cushion carried by said holder.

6. In a device of the character described, the combination with a socket piece adapted 110 to be held in the bore of a spool, of a cylindrical cushion, and a tubular holder for said cushion adapted to be removably held within said socket piece, and provided exteriorly with a projection to engage one end of said 115 socket piece.

In testimony whereof, I have signed this specification in the presence of two subscribing witnesses.

FREDERIC W. HAWKES.
